US00D624885S

(12) **United States Design Patent**
Lin et al.

(10) **Patent No.:** US D624,885 S
(45) **Date of Patent:** ** Oct. 5, 2010

(54) **LED PACKAGE STRUCTURE**

(75) Inventors: **Chen-Hsiu Lin**, Tucheng (TW);
Chih-Chiang Kao, Kaohsiung (TW)

(73) Assignees: **Silitek Electronic (Guangzhou) Co., Ltd.**, Guangzhou (CN); **Lite-On Technology Corporation**, Taipei (TW)

(**) Term: **14 Years**

(21) Appl. No.: **29/354,644**

(22) Filed: **Jan. 27, 2010**

(51) **LOC (9) Cl.** 13-03

(52) **U.S. Cl.** D13/180

(58) **Field of Classification Search** D13/180;
D26/2; 257/79, 80, 81, 88, 89, 95, 98, 99,
257/100, E33.058; 313/483, 498, 500; 362/555,
362/800

See application file for complete search history.

(57) **CLAIM**

The ornamental design for a “LED package structure,” as shown and described.

DESCRIPTION

FIG. 1 is a perspective view of a “LED package structure” showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines define portions of the LED package that form no part of the claimed design.
